UNITED STATES PATENT OFFICE

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY

ELECTRIC SWITCH

Application filed May 25, 1925. Serial No. 32,718.

This invention relates to switches for opening and closing electric circuits and has for its object the provision of switches for the purpose named which shall be of improved 5 construction and operation and in which the switch blade may be more readily moved into and out of closed position than is possible in case of switches heretofore constructed.

The invention is exemplified in the combination and arrangement of parts shown in the accompanying drawings and described in the following specification and it is more particularly pointed out in the appended claims.

15 In the drawings—

Fig. 1 is an end elevation of a switch embodying one form of the present invention, the switch blade being shown in section.

Fig. 2 is a transverse section on line 2—2 20 of Fig. 1.

Figs. 3 and 4 are side and end views respectively with parts in section showing a modified form of the invention.

Fig. 5 is a longitudinal section of a different form of the invention.

Fig. 6 is a section on line 6—6 of Fig. 5.

Figs. 7 and 8 are views similar to Figs. 5 and 6 respectively showing a different modification of the invention.

30 Fig. 9 is an end elevation of another form of the invention.

Fig. 10 is a side elevation of the form shown in Fig. 9.

Figs. 11 and 12 are end and side elevations 35 respectively of another modification.

Fig. 13 is a view similar to Fig. 9 but showing the position taken by the segments when the switch is open.

40 In heavy duty switches and especially in the case of switches which are exposed to weather conditions or which are opened only occasionally, difficulty is frequently experienced in moving the blade relative to the fixed contacts. If the parts are corroded, this

45 difficulty is increased and is especially noticeable where the switches are mounted in position where they are not easily accessible. The present invention overcomes these objections and at the same time provides efficient

electrical contact between the relatively movable parts.

In the form of the invention shown in Figs. 1 and 2, the numeral 10 designates a base block from which fingers 11 extend. 55 The fingers 11 are spaced apart and arranged in sets disposed at opposite sides of the switch blade 12. The fingers are provided with slots 13 and a series of rollers 14 are disposed between the fingers of the various pairs and provided with pintles 15 extending 60 through the slots 13. The pintles 15 are loosely journaled in the slots 13 so that the rollers are free to move longitudinally of the fingers 11 and also have a limited movement 65 in a direction transverse to the fingers. Comparatively heavy springs 16 are secured to the blocks 10 and engage the outer faces of the rollers tending to press them inwardly into engagement with the blade 12. Arcing 70 horns 17 may be provided to prevent arcing to the fingers 11. It will be noted that the outer ends of the fingers 11 are curved outwardly as shown at 18 to provide ample pick-up 75 for the blade 12 as it is moved into engagement with the rollers 14.

In Fig. 1, the rollers are shown in full line position at the point where the blade first engages them as the switch is closed. As shown in that figure, the blade is given 80 a wedge shape so that as it enters between the rollers, the rollers are forced outwardly against the force of the spring 16. This insures firm engagement to provide good electrical connection but at the same time permits 85 easy movement of the blade since it travels on freely movable rollers which in turn roll upon the inner surfaces of the springs 16. The blade may be provided with notches 19 having the same radius of curvature as the rollers 14 so that when the blade reaches its innermost position shown in broken lines in Fig. 1, these springs will force the rollers into the notches, thus, insuring 90 good electrical contact and holding the blade in its closed position. The friction between the rollers and spring 16 will prevent the blade and rollers from dropping 95 downwardly, however, a relatively slight force on the blade tending to open it will 100

overcome the spring tension pressing the rollers into the notches 19 so that the blade may be readily opened and when the rollers are once removed from the notches, the taper 5 on the blade will co-operate with the spring pressure to assist in opening the blade. The traveling engagement between the blade and rollers under the force of the spring 16 will assist in breaking any coating on the blade 10 due to corrosion, sleet or other cause and thus, insure a good electrical contact between the rollers and blade.

Where the switch operates in a horizontal position or in any position in which the rollers do not gravitate to the extreme end of their travel as shown in Fig. 1, resilient means may be employed to move the rollers to their outermost position when they are free from the blade. Such an arrangement 15 is shown in Figs. 3 and 4 of the drawing. In those figures, arms 20 are connected to the base block 10 outside of the springs 21 and these arms are provided with flanges 22 having slots 23 therein for retaining the rollers 20. A resilient roller may be employed as 25 shown in this figure. A head 25 is carried on a plunger 26 which slides in an opening 27 in the base block 10 and is forced outwardly by a spring 28. The head 25 bears 30 against the rollers 24 and move them into their outermost position whenever they are free from the blade 12. Pick-up members 28 similar to the members 18 in Fig. 1 are 35 formed on the arms 20.

In the form of the invention shown in 40 Figs. 5 and 6, balls 30 constitute the rollers for the blade 31 and are set in retainers 32 which move between flanges 33 and are guided by slots 34 and lugs 35. Back plates 36 are secured to the block 10 to form a backing 45 for springs 37 which carry plates 38 forming runways for the balls 30. Where a number of balls are used, it will be apparent that a plurality of spaced contact points will be provided to form electrical connection between the blade and stationary contacts.

In the form of the invention shown in Figs. 7 and 8, the arrangement is similar to that of Figs. 5 and 6 except that runways 38 are 50 provided with studs 39 extending through openings in the backing plate 36. Coil springs 40 surround the studs 39 and press the runways 38 inwardly.

In the form of the invention shown in Figs. 9 and 10, the blade 40 is arranged to 55 make rolling contact with arcuate segments 41. These segments are fixed to shafts or pins 42 which oscillate about pivot studs 43. Flexible conductors 44 provide electrical connection with the segments 41. Secured to the shafts 42 beyond the end of the blade 40 are control segments 46 to which flexible connectors 47 are secured as shown in Fig. 9. These connectors restrain the segments 60 to open and close in unison with one an-

other. Leaf springs 48 are rigidly fixed to the control segments and tend to move the segments into open position shown in Fig. 13. If the segments are closed, the leaf springs 48 are wound upon the control segments and placed under stress tending to 70 open the segments.

In the form of the invention shown in Figs. 11 and 12, raceways are carried by resilient arms 51 and auxiliary springs 52 bear upon the raceways 50 to press them 75 toward each other. The raceways 50 are provided with slots at their inner edges through which ball bearings 53 project to engage the blade 54. The slots in the faces of the raceways are of less width than the diameter of the ball bearings 53 so that the bearings are retained in the raceways.

In disconnecting or high tension switches, particularly those which are used infrequently or which are placed in the open, it is quite common to have the switch held up owing to poor contact or to stick in opening or closing.

The sticking in opening or closing is likely to be occasioned by corrosion of the contacts, loss of the lubricant, or accumulation of dirt, which so increase the coefficient of friction that the switch is opened or closed with difficulty or a much stronger insulator 90 is required to insure safe operation of the switch.

In the present invention, the switch is so made that the accumulation of dirt, corrosion or loss of lubricant, affects the opening or closing of the switch but little. In addition, the switch is such that a very high pressure is permissible between the operating parts without the necessity of causing the component parts of the switch to engage or disengage. In the present invention, the very high pressure which is possible with the small operating force insures contact between the several members. The fact that the area of contact may be made quite small can be used to advantage to insure contact where parts become corroded or coated with dirt or sleet. The low working temperature of a switch under severe conditions depends more upon the pressure than upon the area of contact.

A conducting surface which makes contact at several different points can conduct a large current without a high loss as the total resistance is small. This is due to the fact that the path of the current increases quite rapidly as the current flows away from the point of contact. On switch parts having large areas of contact, the current is frequently carried at a few points and not over the whole surface, as the air or lubricating field may only be broken down at a few points unless excessive pressure is used.

This invention makes use of the high pressure in establishing contact, does away with the necessity of lubricant, and makes it pos-

sible to construct a switch which can be readily operated at all times.

The general principle of the roller contact in connection with the blade may be accomplished in one of several ways, such as with a number of rollers used in a single or multiple by a series of balls operating in slots or cages, or by segments or rollers to which conducting members are attached. In the case of the solid or flexible rollers or balls used for making contact, it is not necessary to provide pig tails or conducting members.

In very heavy current switches where the parts may be quite rigid and of a high degree of accuracy, the flexibility may be taken up in the rollers or on the blades making contact. While the operation of the switch blade will tend to leave the various rolling contact members in proper position for the closing of the switch, it may be necessary to turn the mechanism so that gravity will seat the members properly or to use springs to see that they are in proper position for the closing of the switch. While the various drawings show only a single blade, it is seen that the construction is suitable for multiple blades as it is common practice.

I claim—

1. An electric switch having relatively movable switch members and roller contact means on one of said members for making rolling contact with the other of said members, said members being arranged to bear on substantially diametrical opposite sides of said roller contact means to provide electrical connection said roller contact means having its axis of rotation freely movable relative to the member on which it is mounted in a direction parallel to the surface of said member.

2. An electric switch having relatively movable switch members and a roller contact element for making electrical connection between said members, said roller contact element being free to move bodily relative to both of said switch members and having rolling contact with both of said switch members.

3. An electric switch having relatively movable switch members, one of said members having a resiliently held roller contact element for making electrical connection with the other of said members, said roller contact element being free to move bodily relative to both of said switch members and having rolling contact with both of said switch members.

4. An electric switch having relatively movable switch members, rollers mounted on one of said members, and springs for pressing said rollers toward each other to make electrical engagement with the other of said members, said rollers being free to move bodily relative to both of said switch members and having rolling contact with both of said switch members.

5. An electric switch comprising relatively

movable switch members having surfaces disposed in registration when said switch is closed, and a roller interposed between said surfaces and having rolling contact with both of said surfaces when said members are moved relative to each other.

6. A switch comprising a pair of relatively movable members and a roller having rolling contact with both of said members during relative movement of said members, one of said members having a recess therein to engage said roller when said switch is in closed position.

7. A switch comprising spaced fixed contact members, rollers connected with said members but having their axes of rotation freely movable relative to said members in the direction of the contact surfaces of said members, springs for pressing said rollers inwardly, and a blade movable into and out of position between said rollers.

8. A switch comprising spaced fixed contact members, rollers associated with said members and movable relative thereto, springs having flanges engaging said rollers along which said rollers are arranged to travel, and a blade movable into and out of position between said rollers, said blade having a recess therein for cooperating with one of said rollers to retain said blade in closed position.

9. A switch comprising a base block having a plurality of fingers arranged in sets projecting therefrom, rollers loosely carried by said fingers and disposed in registration with each other, the axes of rotation of said rollers being movable in the direction of the length of said fingers, springs bearing against the outer faces of said rollers, said fingers having outwardly curved portions, and a blade movable into and out of position between said rollers, said blade having elongated grooves on opposite faces thereof for engaging said rollers to retain said blade in closed position.

10. In combination a pair of relatively movable switch elements, a roller interposed between said elements and having rolling contact with both of said elements throughout the entire range of relative movement of said elements, said roller being arranged to limit the movement of said elements toward each other and to provide electrical connection between said elements when said switch elements are in their normal closed position.

11. An electric relatively movable switch comprising a pair of switch elements having contact faces arranged substantially parallel with each other and a roller interposed between said faces and free to travel equally on said faces when said elements are relatively moved and arranged to prevent contact of said faces for all closed positions of said switch.

12. An electric switch comprising a pair

of switch elements, one of which is movable and roller bearing means interposed between said elements and constituting the sole connection between said elements for all closed positions of said switch, said roller bearing means being free to travel equally relative to both of said elements when said switch is moved out of closed position.

13. An electric switch comprising a pair of relatively movable switch elements having substantially parallel opposed faces and roller bearing means interposed between said faces and holding said faces apart and constituting the sole electrical connection between said switch elements for all closed positions of said switch, said roller bearing means being free to roll equally on both of said opposed faces when said switch is opened.

14. An electric switch comprising a movable switch blade, a roller bearing upon which said blade rides for all closed positions of said switch and a supporting surface along which said bearing rolls when said blade is moved from its closed position.

15. An electric switch comprising fixed and movable contact members, roller bearing means interposed between said members and upon which said movable member rides when said switch is closed, said bearing means being free to roll along the surface of said fixed member, said movable member being poised upon said roller bearing when in normal closed position to facilitate opening of said switch from said closed position.

16. An electric switch comprising a pair of contact members, movable relative to each other, roller bearing means interposed between said members and upon which said members are poised when said switch is in normal closed position to permit easy opening of said switch, said bearing means being free to roll along the surface of both of said members, one of said members having a depression therein to form a seat for said roller bearing means when said switch is closed to prevent accidental opening of said switch.

17. An electric switch comprising a pair of contact members having substantially parallel opposed faces movable relative to each other in a direction parallel to said faces and roller bearing means interposed between said faces and free to roll along both of said faces, said faces being poised upon said roller bearing means when said switch is in its normal closed position to provide electrical connection between said contact members and to facilitate opening of said switch.

18. An electric switch comprising a fixed contact member and spaced roller bearing means thereon, said bearing means being free to travel along said fixed contact member, and a blade movable into position between said roller bearing means to form electrical connection through said roller bearing means with said fixed contact member, said blade be-

ing poised between said roller bearing means when said switch is in its normal closed position to facilitate movement of said blade out of said closed position.

19. An electric switch comprising a fixed contact member, a blade movable into and out of electrical connection with said contact member, said blade and contact member having substantially parallel contact faces and roller bearing means interposed between said faces and free to roll along both of said faces, said blade being poised upon said roller bearing means when in its normal closed position to permit easy movement of said blade out of said position.

In testimony whereof I have signed my name to this specification on this 21st day of May, A. D. 1925.

ARTHUR O. AUSTIN.
